UNITED STATES PATENT OFFICE.

CHARLES H. COCHRANE, OF CHICAGO, ILLINOIS.

PRINTING PRESS.

Application filed July 17, 1924. Serial No. 726,419.

This invention relates to improvements in printing presses, and particularly to that type of printing press wherein type is set in a form and means are provided for inking the form, and other means are employed to bring the sheet to be printed upon in front of a platen operating to press the sheet against the type form.

The principal object that is sought to be attained is that of acceleration of the printing operation without undue jar or strain. One of the objects of the invention is to so organize the press that the necessary elementary movements will be minimized as far as possible, both in the operation of inking the type, and also that of delivering the paper to be printed upon before a platen and withdrawing the same after printing,—all looking to increased speed and consequently greater production, without certain undue strains which have been heretofore found in presses of this general nature.

A preliminary description of the device as illustrated in the drawings and more fully described in detail is as follows. A type form is suitably mounted within a circumferential drum, the type face coming to the surface of a flattened segment of the drum. The periphery of the drum is employed as a guide for oppositely disposed sets of ink rolls, which are suitably and oppositely mounted on radial arms, with means to rotate said arms so as to cause the rolls to traverse the path of the circumference of the drum and also the face of the type form.

By providing said oppositely disposed rolls with suitable inking means for the same, I am able to traverse the face of the type form with every semi-revolution of the roller-carriage. This is an important factor, for it has been found that if only one set of ink rolls is provided, the movement of said rolls at a speed sufficient to traverse the ink faces once in every revolution will cause such a violent vibration in the mechanism as to be impractical. Another feature of the mechanism is the special platen embodying the soft yielding impression blanket or surface under the tympan. This reduces the impressional force necessary and so reduces the strain on the machine.

Another important phase of the invention lies in the fact that I provide means by which the sheet to be printed upon is taken from a platform placed in very close prox-

imity to the place of impression, and delivered by a limited arcuate movement into a position before the type and between the type and the platen, and at the same time 60 and by reason of the same arcuate movement I pick up a sheet from a pile and deliver the same on to a platform from which such sheet may be again picked up and delivered as stated. Furthermore, I provide 65 means by which, when the printing is done, the sheet may be withdrawn downwards and delivered to a discharge receptacle. The picking up of the sheets and the withdrawal of the same is done by the medium of a vacuum. As previously stated, the purpose of my invention is to provide means by which the sheets of paper to be printed may be picked up at a point relatively near the space lying between the platen and the type, and 70 carried to a printing position, and withdrawn therefrom after the printing operation, without one operation delaying the other, as is now usual. At the same time that the sheet is being delivered between the 75 platen and the type, I pick up another sheet and place it on a platform where it can be again picked up and delivered.

A more detailed description of my invention is shown in the following drawings, 80 wherein the several parts of the mechanism are indicated by numerals, like parts being designated by like numerals. As the machine is symmetrical about the center line A—A I have shown only one side in the plan 85 view. Parts in the side not shown are designated by the letter "a" following the numeral by which the corresponding part shown is indicated; for example, 29 indicates the connecting rod shown, whereas 29^a indicates 90 a corresponding part on the side not shown.

Fig. 1 is a side elevation of the press showing in full lines the platen in the open position and in dotted lines the platen in the closed position;

Fig. 2 is a half plan view, both sides being symmetrical;

Fig. 3 is a section of the bed and drum on the center line A—A;

Fig. 4 is a side elevation showing the 105 platen in the closed position in full lines and in the open position in dotted lines; and

Fig. 5 is a side elevation in detail of the platen.

The type bed 1 is stationary and is fixed 110 on the hollow shaft 2 between the spaced side frames 3 and 3^a of the press frame. The

shaft 2 extends transversely between the side frames 3 and 3^a and has its ends secured thereon, and is counterbalanced by the weight 4. A pair of duplicate double 5 form roller carriages 5 and 5^a are rotatably mounted on the shaft 2 on the inside of and adjacent respective side frames 3 and 3^a, the type bed 1 being disposed between these roller carriages. Two duplicate gears 6 and 10 6^a surround the shaft 2 for rotation with respect thereto and are disposed between respective roller carriages 5 and 5^a and side frames 3 and 3^a and are secured with respective roller carriages 5 and 5^a for driving the same. The power shaft 23 extends transversely across between the side frames 3 and 3^a out of the path of rotation of the roller carriages 5 and 5^a and is mounted for rotation in the side frames, this shaft constituting the drive shaft of the press and being driven from a suitable source of power not shown. The roller carriages 5 and 5^a are driven from the shaft 23 in synchronism and in angular alignment by 15 means of duplicate idler spur gears 7 and 7^a disposed on the insides of and adjacent respective frames 3 and 3^a and mounted for rotation thereon and meshing with respective spur gears 6 and 6^a and duplicate spur 20 gears 8 and 8^a secured on the shaft 23 and disposed on the insides of and adjacent respective frames 3 and 3^a and meshing with respective gears 7 and 7^a. Ink rollers 9 and rider rollers 10 are carried at the diametrically opposite ends of the roller carriages 5 and 5^a and extend transversely therebetween, springs 12 yieldably urging the rollers inwardly with the axles of the rollers engaged in radial slots 13 in the roller carriages. In the rotation of the roller carriages the rollers 9 bear on bearers 11 and 11^a and pass entirely around the type bed 1, the shaft 23 being disposed out of the path of the ink rollers 9 and 10 as well as that of 25 the roller carriages.

An ink fountain of usual construction, not shown, supplies ink to the ink cylinder 14 extending transversely across between and rotatably mounted on the side frames 3 and 3^a. The ink roller 15 is mounted on arms 16 and 16^a pivoted on respective side frames 3 and 3^a, and cranks 17 and 17^a, rotatably mounted on respective side frames, operate the arms 16 and 16^a through connecting rods 18 and 18^a, the cranks 17 and 17^a being positively driven from the shaft 23 in a usual manner. The axle of the roller 15 is engaged in slots 19 and 19^a in the side frames to engage alternately the roller 15 with the cylinder 14 and the segment plate 20, disposed between the bearers 11 and 11^a in concentric relation with the roller carriages 5 and 5^a, for the transfer of ink from the cylinder 14 to the segment plate 20. The operation of the roller 15 is

so timed that it engages the plate 20 between the two sets of ink rollers 9 and does not interfere with their rotation. The ink rollers 9 pass about and contact the segment plate 20 in their rotation for the distribution of ink thereon and they in turn ink the printing form 21, which is fixed within the chase 22 on the bed 1, for printing therefrom, the rider rollers 10 in their contact with the rollers 9 serving to aid in the distribution 75 of the ink.

Secured on the power shaft 23 on the outside of one of the side frames 3 and 3^a is another gear 24, and this gear meshes with an idler gear 25 mounted on the outside of the adjacent side frame, and the gear 25 meshes with a crank gear 26 secured on a revoluble shaft 28 extending transversely through the bore of the shaft 2 whereby the shaft 28 is driven in timed 80 relation with the roller carriages 5 and 5^a, the shaft 28 making two revolutions to one revolution of the roller carriages. Secured on the shaft 28 on the outside of the other side frame is a crank 27, and connecting rods 29 and 29^a are pivotally secured respectively with the crank gear 26 and the crank 27 and a transverse shaft 31 secured to the platen 30 for reciprocating the platen. The platen is pivotally mounted by means 90 of transversely spaced arms 32 and 32^a extending downwardly and journaled upon a transverse shaft 33 extending between the side frames 3 and 3^a and mounted thereon. A spring 34 imparts a reaction thrust to 100 the platen at the outer reversal thereof.

The nippers 35 and 35^a mounted on the swinging frame 36, which is reciprocated by the crank 66 and the connecting rod 67, enter the press-jaw from above. They are 105 connected by the suction cross bars 37 and 38, which are perforated and connected by the flexible tubing 39 and 40 to the vacuum pump 55. Horizontal movement of the nippers when in the closed position is allowed 110 for by the sliding head 41. 42 is a platform fitted with guide 43 which is operated by lever 44.

The suction gripping arms 45 and 45^a for withdrawal of the sheet are joined by the 115 suction cross bar 46 which is perforated and connected by the flexible tubing 47 to the vacuum pump 55. The arms 45 and 45^a pivoted on arms 48 and 48^a, which are fixed to rocker arms 32 and 32^a, are oscillated by 120 the crank 49 and connecting rod 50. Crank 49 is rotated by a suitable train of gears as 65. 51 is the delivery slide for the printed sheets. The perforated pipes 52 are connected by the flexible tubing 53 with the 125 pressure pump 55. 54 is a well-known type of heater. The combined vacuum and pressure pump 55 is connected through valves (not shown) with the suction tubing 39, 40 and 47, and with the pressure tubing 53. 130

These valves are timed by a suitable mechanism to open at the proper time.

Fig. 3 is a detail of the bed showing the type form 21 fixed within the chase 22 on the bed 1. The ink rollers 9 are about to ink the type form, while the opposite set of ink rollers are about to come in contact with the segment ink plate 20.

Fig. 4 shows the platen 30 in the closed position with nippers 35 and 35^a holding the sheet against the platen. The suction gripping arms 45 and 45^a are in position to receive the sheet as soon as it is released by the nippers and platen.

Fig. 5 illustrates a removable packing on the front surface of the platen 30. This consists of a sheet of soft rubber 56, over which is placed a thickness of binders hard press-board 57 and on these two or three sheets of paper 58, the top sheet of which is termed the tympan. The tympan and packing are held by the clamps 59 to the iron base 60 which is secured to the platen by the points 61 and the catch 62. 63 is the pile of blank paper. 64 is the pile of printed sheets on the delivery truck.

The operation of the press is as follows:

The type form 21 is secured within the chase 22 on the bed plate 1.

Ink is delivered by the ink roller 15 from the ink cylinder 14 to the segment ink plate 20. The ink is picked up from the segment ink plate 20 by the ink rollers 9 and transferred to the type form 21. The springs 12 pull these rollers in against the bearer rail 11, segment ink-plate 20 and the type form 21.

The paper is fed in two movements by the nippers 35 and 35^a. The first swing of the frame 36 brings a sheet from the pile 63 to the table 42 by means of the suction cross bar 38. The pile of blank paper 63 is maintained at the proper level by a screw elevating mechanism not shown. In the next swing the suction cross bar 37 picks the sheet from the platform 42, the guide 43 having been lowered by the lever 44, and delivers the same between the jaws formed by the type form and the platen. When the platen 30 is about one inch from the type form, the sheet is gripped between the nippers 35 and 35^a and the platen 30. The remaining inch of travel is provided for by the sliding head 41. At the same time that the suction cross-bar 37 is carrying the sheet into the printing position, the suction cross bar 38 is bringing a second sheet from the pile 63 to the table 42. After printing, the platen recedes and the suction cross bar 46 jerks the sheet down and deposits it on the slide 51, from which it goes to the delivery pile 64 on the truck. The blowing pipes 52 expedite the delivery. The sheet passes under the flame from the heater 54 whereby

any charge of static electricity is removed 65 and the drying of the ink hastened.

Claims:

1. In a printing press the combination with spaced side frames, of a hollow support extending transversely between said side frames and secured therewith, a type bed and an ink plate carried by said support between said side frames and arranged angularly about said support, a reciprocable platen cooperating with said type bed, a pair of roller carriages disposed between respective side frames and said type bed and ink plate and mounted for rotation about said support, ink rollers extending between and carried by said roller carriages for contact with said ink plate and a printing form on said type bed, a transverse drive shaft carried by and extending across between said side frames out of the path of said roller carriages and ink rollers, a pair of gear 80 trains disposed on the outsides of respective roller carriages for driving said roller carriages in synchronism from said drive shaft, a crank shaft extending transversely and through said hollow support, cranks on said crank shaft on the outsides of respective side frames for reciprocating said platen, and a third gear train for driving said crank shaft from said drive shaft in timed relation with said roller carriages. 95

2. In a printing press the combination with spaced side frames, of a hollow support extending transversely between said side frames and secured therewith, a type bed and an ink plate carried by said support between said side frames and arranged angularly about said support, a reciprocable platen cooperating with said type bed, a pair of double roller carriages disposed between respective side frames and said type bed and ink plate and mounted for rotation about said support, two sets of ink rollers extending between and carried by said roller carriages at diametrically opposite ends of the roller carriages for contact with said ink plate and a printing form on said type bed, a transverse drive shaft carried by and extending across between said side frames out of the path of said roller carriages and ink rollers, a pair of spur gear trains disposed in respective planes between said side frames and adjacent roller carriages for driving said roller carriages in synchronism from said drive shaft, a crank shaft extending transversely and through said hollow support, cranks on said crank shaft on the outsides of respective side frames for reciprocating said platen, and a third spur gear train on the outside of one of said side frames for driving said crank shaft from said drive shaft, said pair of gear trains and said third gear train being so proportioned as to effect two revolutions of said 100

105

110

115

120

125

crank shaft to one revolution of said roller carriages.

3. In a printing press the combination with spaced side frames, a type bed and ink plate disposed between said side frames and arranged angularly about a transverse axis, support means extending on said axis inwardly from said side frames for supporting said bed and ink-plate therefrom, a reciprocable platen cooperating with said type bed, a pair of roller carriages disposed between respective side frames and said type bed and ink plate and mounted for rotation on said axis about said support means, ink rollers extending between and carried by said roller carriages for contact with said ink plate and a printing form on said type bed, a pair of coaxial revoluble cranks disposed on the outsides of respective of said side frames for reciprocating said platen, and means for rotating said carriages and cranks in synchronism.

4. In a printing press the combination with spaced side frames, a type bed and ink plate disposed between said side frames and arranged angularly about a transverse axis, support means extending on said axis inwardly from said side frames for supporting said bed and ink plate therefrom, a reciprocable platen cooperating with said type bed, a pair of roller carriages disposed between respective side frames and said type bed and ink plate and mounted for rotation on said axis about said support means, ink rollers extending between and carried by said roller carriages for contact with said ink plate and a printing form on said type bed, a pair of revoluble cranks disposed on said axis and on the outsides of respective of said side frames, and means for rotating said carriages and cranks in synchronism. 40

Signed by me at Springfield, Ohio, this 12th day of July, 1924.

CHARLES H. COCHRANE.
